(57) CLAIM

The ornamental design for a merchandise display case, as shown and described.

DESCRIPTION

FIG. 1 is a top, front perspective view of a merchandise display case of our new design;

FIG. 2 is a front view thereof; and,

FIG. 3 is a elevational view of the left side thereof with the right side being a mirror image.

The surface(s) or portion(s) of the article not shown in the drawing or described in the specification form(s) no part of the claimed design.

The broken lines showing a microwave above and a freezer below are for illustrative purposes only and form no part of the claimed design.

1 Claim, 2 Drawing Sheets

FIG. 3
